UNITED STATES PATENT OFFICE.

RANSOM J. SMITH, OF GEORGIA, VERMONT.

CHIMNEY-CAP.

SPECIFICATION forming part of Letters Patent No. 282,392, dated July 31, 1883.

Application filed April 5, 1883. (No model.)

To all whom it may concern:

Be it known that I, RANSOM J. SMITH, a citizen of the United States of America, residing at Georgia, in the county of Franklin and State of Vermont, have invented certain new and useful Improvements in Chimney-Caps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a cap to be placed upon a chimney for increasing the draft and preventing downward currents of air from entering the chimney. The construction and operation of the invention will be fully understood from the following particular description, in connection with the accompanying drawings, in which—

Figure 1 is a side elevation of my improved chimney-cap. Fig. 2 is a vertical section of the same; and Fig. 3 is a horizontal section on the line *x x*, Fig. 1.

The letter *A* indicates a base-plate, which is to rest upon the top of the chimney, and is provided with a central opening, from which projects downward a sleeve, *B*, which enters the mouth of the chimney. From the top of the base-plate, and surrounding its central opening, projects a collar, *C*, upon which is fitted a flaring hood, *D*, covered by a conical cap, *E*. This cap may be, however, of any other desired shape. In the side wall of the hood *D* are formed at intervals oblong openings *f*, at the longitudinal centers of which are secured angular deflecting-plates *G*, having inwardly-extending diverging wings *g*, the inner edges of which are separated by intervening spaces from the edge-walls of the opening. Upon the outer side of the hood are secured guard-plates *H*, transversely bent to conform approximately to the shape of the hood. These guard-plates cover the openings in the hood, but stand out at a little distance from the wall of said hood, so as to allow the escape under their edges of air or smoke passing outwardly through said openings.

The operation of my invention, as now described, is as follows: When the smoke and heated air rise from the chimney and pass through the sleeve *B* to the hood, draft-cur-

rents are caused at the contracted openings on 55 each side of the deflecting-plates, and the products of combustion are then directed outwardly, as indicated by the arrows in Fig. 3, and escape past the edges of the guard-plates. These guard-plates have the double function 60 of serving as the walls of draft-passages which continue the draft even after the products of combustion leave the hood, and by covering the openings in said hood they prevent lateral air-currents from entering the same and passing down the chimney. If currents of air strike under these guard-plates at one edge, 65 they are met by the deflecting-plates *G* and pass off under the opposite edges of the guard-plates.

From an inspection of the drawings it will be readily seen that a very efficient draft is created by the deflecting-plates alone, and that this draft is very much re-enforced by the guard-plates, in addition to the function of the latter in preventing air-currents from entering 75 the chimney.

It has been found in practice that my improved chimney-cap prevents the smoking of stoves and fire-places, and obviates the accumulation of soot and dripping of creosote, while at the same time prevents excessive drafts in high winds.

Having now fully described my invention, 85 what I claim is—

1. In a chimney-cap, the combination, with the hood *D*, having openings at intervals in the wall thereof, of the angular deflecting-plates *G*, arranged in said openings, and the guard-plates standing outside of said openings 90 and covering the same, substantially as described.

2. In a chimney-cap, the combination, with the base-plate *A*, having a central opening, and provided with the depending sleeve *B* and upwardly-projecting collar *C*, of the covered funnel *D*, fitted upon said collar and provided with openings at intervals in its wall, the deflecting-plates *G*, and the guard-plates *H*, all constructed and arranged substantially as described.

In testimony whereof I affix my signature in presence of two witnesses.

RANSOM J. SMITH.
